UNITED STATES PATENT OFFICE

102,960

DESIGN FOR A DISPENSING VEHICLE BODY

Morris H. Shield, Chicago, Ill.

Application May 12, 1936, Serial No. 62,606

Term of patent 3½ years

To all whom it may concern:

Be it known that I, Morris H. Shield, a citizen of the United States, residing in Chicago, Cook County, Illinois, have invented a new, original, and ornamental Design for a Dispensing Vehicle Body, of which the following is a specification, reference being had to the accompanying drawing, forming a part thereof.

I claim:

The ornamental design for a dispensing vehicle body, substantially as shown.

MORRIS H. SHIELD.
